UNITED STATES PATENT OFFICE.

IRVEN H. WILSEY, OF CHICAGO, ILLINOIS, ASSIGNOR TO CHARLES H. MEYER,
TRUSTEE, OF CHICAGO, ILLINOIS.

AUTOMATIC PRIMING DEVICE AND METHOD.

Application filed July 8, 1921. Serial No. 483,165.

To all whom it may concern:

Be it known that I, IRVEN H. WILSEY, a citizen of the United States, residing at Chicago, in the county of Cook and State 5 of Illinois, have invented certain new and useful Improvements in Automatic Priming Devices and Methods, of which the following is a specification.

This invention relates to priming devices 10 for internal combustion engines. One of the principal objects of the invention is to provide a device of this kind which operates entirely automatically to supply a charge of pure fuel to the engine upon the initial 15 movements thereof.

Another object is to utilize the pressure developed in one or more of the cylinders as the engine is turned over to operate the 20 priming device so that a priming charge of pure fuel is injected at the proper interval to insure easy starting of the engine.

Another object is to provide a novel 25 method of priming an internal combustion engine which consists in utilizing the variations in pressure in the cylinder to draw a charge of pure fuel from the fuel supply source and forcing this charge into the engine cylinder as a priming charge to render it easy to start the engine.

A still further object of the invention is 30 to provide a novel method of and means for storing energy from a moving motor and automatically utilizing such energy after the stopping of the motor.

Other objects will appear in the progress 35 of the following detailed description, which is to be read in connection with the accompanying drawing wherein Figure 1 is a side elevation of an engine equipped with the priming device of my invention. Fig. 40 2 is a central vertical section of the device taken on line 2—2 of Fig. 3. Fig. 3 is a plan view. Fig. 4 is an under side plan of the cover plate of the device and Fig. 5 is a 45 central vertical section of the injector nozzle used in connection with the device for spraying the priming charge into the intake manifold of the engine.

Throughout the views the same reference 50 numerals are applied to the same parts.

Referring to the drawing, the reference numeral 6 is applied generally to the priming device which preferably is mounted in the cylinder head over one of the cylinders in the block 7. The engine has exhaust and 55 intake manifolds 8 and 9, in the latter of which is threaded the injector nozzle 10 designed to spray a priming charge of pure fuel into the manifold. The fuel is conducted to the nozzle 10 through the tube 11 60 connected to the device 6. A second tube 12 is provided which connects the device 6 with a source of fuel supply which may be either the main fuel tank, the vacuum tank or the float chamber of the carburetor 65 of the engine, whichever is most convenient for attachment.

The device 6 comprises a cup-shaped storage receptacle 13 which is closed by a flanged cover plate 14 fastened securely thereon by 70 means of a plurality of screws 15 to form an air tight chamber. Threaded into an opening in the bottom of the receptacle 13 is a bushing 16 secured by a lock nut 17. The bushing 16 protrudes into the receptacle 75 and is there permanently secured to the bottom wall of a metal bellows 18. Although any suitable form of pressure responsive means may be utilized such as a diaphragm or the like, I prefer to provide for this purpose a metal bellows such as that illustrated.

The metal bellows is closed at its upper end by a head plate 19 which has a central opening closed by a plug 20. A coiled tension spring 21 is connected between the plug 85 20 and the bushing 16 by means of nipples 22 and serves normally to compress the metal bellows to substantially the size shown in Fig. 2.

The bushing 16 is connected with a nipple 90 23 which threads into the cylinder head and establishes communication between the interiors of the cylinder and the metal bellows 18. A ball closure 24 seats downwardly upon a seat 25 in the nipple 23 and has a bleeder 95 hole or bypass 26 extending diametrically therethrough. A stem 27 which is fixed at its upper end in the wall of the nipple 23 has a reduced lower portion received in the bypass 26. The ball 24 is limited in its upward 100

movement by an annular shoulder 28 formed by the reduced portion of the stem 27. Carbon or oil lodging in the bypass 26 is readily cleaned out by the ball reciprocating with respect to the stem as it repeatedly seats and unseats in the operation of the engine.

The receptacle 13 has a fuel inlet valve 29 and an outlet valve 30 which are carried on stems connected to levers 31 and 32, respectively, pivoted in posts 33 depending from the cover plate 14. The inlet valve 29 is arranged to seat upwardly on a seat 34 in a sleeve 35 threaded in the neck portion 36 of the cover plate 14. The neck 36, similarly to the neck 37, may be threaded or otherwise permanently secured to the plate 14 to form a sealing connection therewith or, if desired, these parts may be formed integral with the plate. A comparatively light coiled tension spring 38 acting between the sleeve 35 and a stop knob 39 on the end of the stem of the valve 29 normally holds the valve 29 closed. A heavier tension spring 40 connected between the valve 29 and the free end 25 of the lever 31 has sufficient tension so that when it is stretched, upon swinging of the lever 31, it overcomes the tension of the spring 38 to unseat the valve 29.

The outlet valve 30 is cup-shaped similarly to the inlet valve 29. By so forming these valves the action of the liquid fuel passing the valves is made available to assist in opening the valves. The valve 30 seats downwardly on a sleeve 41 threaded into the neck portion 37. Both the sleeve 41 and the sleeve 35 are adjustable and are arranged to be locked in adjusted position by lock nuts 42. A coiled tension spring 43 is connected between the free end of the lever 32 and the 40 end of the stem of the valve 30 so that the valve 30 is normally held closed. The tube 11 previously referred to has connection with the neck 37 and the tube 12 with the neck 36. A removable plug 44 is provided 45 in the cover plate 14 to admit the initial charge of fuel to the storage receptacle and to permit the operator to replenish the fuel in the receptacle where there has been considerable leakage at the joints either in the 50 device itself or in its connections with the fuel supply source.

The outlet tube 11 is connected to the injector nozzle 10 by a nut 45 which, as shown in Fig. 5, clamps down upon the flanged end 55 of the tube 11. The nozzle 10 is arranged to thread into the wall of the intake manifold 9 and has a restricted discharge orifice 46 for spraying the pure fuel in its raw form into the manifold on starting the engine. 60 Where desired, nozzles corresponding to the nozzle 10 may be provided in varying numbers in proportion, for example, to the number of cylinders which the engine has and, if desired, these nozzles may be made to 65 discharge directly into the engine cylinder.

The device is arranged to operate in the following manner: Assuming that the storage receptacle 13 has been supplied with an initial supply of fuel and that the pipe 12 leading to the fuel supply source is also 70 filled so that there is a substantially solid column of fuel extending from the receptacle to the supply source, the moment the engine is turned over in starting, the pressure developed in the engine cylinder is 75 communicated to the interior of the metal bellows 18. The metal bellows expands and lifts the plate 19 against the tension of its spring 21 and fuel is forced out of the receptacle 13 past the valve 30 through the 80 tube 11 and into the intake manifold through the injector nozzle 10. The moment the valve 30 opens, the sub-atmospheric pressure existing in the intake manifold is communicated to the interior of the storage receptacle 85 so that the metal bellows, the interior of which is subjected to comparatively high pressure, advances the plate 19 rapidly because of the disparity in pressure. The plate 19 rises very quickly until it engages 90 the levers 31 and 32.

In this upward movement, until the plate 19 engages the levers 31 and 32, a rich spray of fuel is emitted from the discharge orifice 46 of the nozzle 10. When the plate 19 engages the levers 31 and 32, the spring 43 is stretched, closing the outlet valve 30. At the same time the tension spring 40 is stretched sufficiently to overcome the tension 100 of the spring 38 so that the valve 29 is opened. The downward movement of the valve 29 is limited by the stop knob 39 on the end of its valve stem.

The plate 19 remains in engagement with the levers 31 and 32 until the engine ceases 105 to operate. When the engine stops, the pressure in the cylinders soon returns to normal atmospheric so that the metal bellows 18 under the action of its spring 21 commences 110 to recede, the pressure within the metal bellows being trapped by the valve 24 is permitted to bleed through the restricted bypass 26 into the engine cylinder. As the plate 19 recedes the levers 31 and 32 are released thereby replacing the valve 29 under 115 the action of its spring 38 which closes it lightly. A reduction in pressure is also created within the storage receptacle because of the receding of the plate 19. This reduction 120 in pressure is sufficient to overcome the tension of the spring 38 to unseat the valve 29 and a quantity of fuel is drawn in from the supply source through the tube 12. The valve 29 does not move from its seat sufficiently to cause the stop knob 39 to engage 125 the end of the sleeve 47 which threads into the lock nut 42. The valve 29, in other words, is in floating relation to its seat and permits the passage of fuel until a reduction 130 in pressure no longer exists within the stor-

age receptacle which is when the metal bellows has reverted to its normal size. The valve 29 thereupon closes, leaving the device in readiness for supplying a priming charge 5 to the engine when the engine is started again.

The initial pressure produced in the bellows by the compression in the cylinder is accompanied by a rise of the bleeder valve 10 24. The subsequent reduction in pressure in the cylinder operates to close the valve 24 on the seat 25. The leakage through the bypass 26 is sufficiently slow so that in the time between compression strokes there is 15 substantially little change in the volume of gas within the bellows. Hence, in the continuous operation of the engine the expanded position of the bellows is substantially unchanged and no pumping action is exerted thereby.

From the foregoing description it will appear that the priming device which I have provided operates entirely automatically and requires little or no attention once it 25 has been properly installed. It will, of course, be understood that the specific details of construction are merely illustrative and are capable of variation so as still to partake of the more important advantages 30 of my invention. In the subjoined claims it is therefore aimed to include all legitimate modifications and adaptations properly coming within the spirit and scope of the invention.

35 What I claim is:

1. In combination with an internal combustion engine, means for supplying a priming charge of fuel to said engine comprising an expansible storage chamber communicating with said engine and also with a fuel supply, said chamber being adapted to contain a charge of fuel, and a member adapted to be operated by the pressure developed in the cylinders of said engine to 40 45 eject the fuel from said chamber.

2. In combination with an internal combustion engine, a priming device for supplying a priming charge of fuel to said engine having a member adapted to be moved from its normal position by the pressure in one or more of the cylinders of the engine in operation to eject a charge from said device to the engine, said member being adapted to return to normal position when said engine ceases to operate and in so doing to draw a quantity of fuel to 50 55 said priming device to recharge the same.

3. An automatic priming device for internal combustion engines comprising a storage receptacle, and resilient means adapted to operate automatically in one direction when said engine is at rest to supply a quantity of fuel to said receptacle, said means being adapted to be operated 60 65 in the opposite direction when said engine

is operated to eject the fuel as a priming charge to said engine.

4. A priming device for an internal combustion engine comprising a storage receptacle, and spring operated means adapted 70 to operate automatically as a suction pump while the engine is idle to supply a quantity of fuel to said receptacle, said means being adapted to be operated as a force pump by the engine when the same is operated 75 to feed the fuel as a priming charge to said engine.

5. In combination with an internal combustion engine, a primer comprising an expansible storage chamber communicating 80 with said engine and also with a fuel supply, said chamber being adapted to be charged with fuel while the engine is idle, and means for communicating to said chamber pressure developed in the cylinder of 85 the engine upon initial operation thereof to eject the fuel from said chamber to prime the engine.

6. In a priming device for an internal combustion engine the combination of a 90 storage receptacle, a diaphragm member, spring means normally retracting said member to draw fuel into said receptacle, said member being adapted to be expanded 95 upon the initial operation of the engine by the pressure developed in the cylinders thereof to eject the fuel from said receptacle to be fed to said engine as a priming charge, and a valve between said diaphragm 100 and the engine arranged to maintain said diaphragm expanded during the operation of the engine, said valve having a bypass adapted to permit said diaphragm to be retracted when the engine ceases to operate.

7. In a priming device for an internal combustion engine, the combination of a storage receptacle, a pressure responsive member, means normally causing said member to recede to draw fuel into said receptacle, said member being adapted to be advanced 105 upon operation of the engine by the pressure developed in the cylinders thereof to eject the fuel from said receptacle to be fed to the engine.

8. In a priming device for internal combustion engines, the combination of a storage receptacle, a pressure responsive member, means tending to cause said member to recede to draw fuel into said receptacle, said member being adapted to be advanced 110 upon operation of said engine to eject the fuel from said receptacle to be fed to said engine.

9. In a priming device for an internal combustion engine, the combination of a storage receptacle, a pressure responsive member, means for moving said member to receded position to draw fuel into said receptacle, said member being adapted to be advanced 120 upon operation of the engine to 125 130

eject the fuel from said receptacle to be fed to the engine, and a valve arranged to permit free communication of pressure to said member to advance the same upon the 5 operation of said engine, said valve having a bypass adapted to permit said member to recede when said engine ceases to operate.

10. In a device of the character described the combination with a storage receptacle, 10 a diaphragm for drawing in and ejecting fuel from said receptacle, said diaphragm being arranged to be operated by pressure applied on one side thereof developed in the cylinder of an engine associated with 15 said device, of a valve for regulating the operation of said diaphragm disposed between said cylinder and said diaphragm, said valve comprising a ball closure, a bypass therein, a stem received in said bypass for guiding and limiting the movement of 20 said ball, said stem being smaller than said bypass to permit leakage of pressure past said ball when said engine is at rest, said stem being slidable in said bypass whereby 25 the same is kept clean.

11. In a device of the character described the combination with a storage receptacle, 30 pressure responsive means for drawing in and ejecting fuel from said receptacle, said means being arranged to be operated by pressure applied on one side thereof, of a valve for regulating the operation of said means, said valve having a bypass therein, a member operating in said bypass for 35 guiding and limiting the movement of said valve, said member being arranged to restrict the leakage of pressure past said valve.

12. An automatic priming device for an 40 internal combustion engine for supplying an initial priming charge of fuel to the engine, comprising a member adapted for forcing fuel from said device to the engine but adapted normally to operate when the engine 45 is idle to supply fuel to said device, said member being made to operate upon the initial reciprocations of the pistons in the cylinders of the engine to eject the supply of fuel from said device as a priming 50 charge to the engine.

13. An automatic priming device for an 55 internal combustion engine comprising a receptacle having communication with the engine and a fuel supply source, and means operable normally to draw fuel into said receptacle from said source while the engine is idle and adapted to operate upon the first reciprocations of the pistons in the engine to shut off communication with said source 60 and to force a priming charge of fuel to the engine from said receptacle, the device as a whole being relatively free from fuel while the engine is in operation.

14. The method of priming an internal

combustion engine which consists of trapping 65 the pressure produced by a running motor, maintaining said pressure in a slowly subsiding condition after the stopping of the motor, utilizing the subsiding pressure to draw a quantity of fuel from a supply 70 source, storing said quantity during the idle period of the motor, and forcing said fuel into the motor by the pressure produced when starting the motor.

15. The method of priming an internal 75 combustion engine comprising mechanically starting the motor, utilizing energy from the moving motor to force a quantity of fuel from a storage chamber into the motor, maintaining said storage chamber substantially empty during the operation of the motor, storing energy from the moving motor for use after the stopping of the same, and utilizing said energy to refill the storage chamber with fuel for the next operation of starting.

16. The method of automatically priming 80 an internal combustion engine which comprises storing energy from a moving motor, stopping the motor, utilizing said energy to 90 position a supply of fuel for priming, starting the motor, simultaneously starting the storage of energy from the moving motor, and utilizing a portion of said energy to 95 force the supply of fuel into the motor.

17. The method of storing energy from a 100 running motor comprising compressing a volume of gas in the motor, displacing a movable head by said compressed gas against a resilient means, said resilient means potentially holding the energy, trapping a volume of the compressed gas to maintain the energy potentially, and releasing said compressed gas after stopping the motor to release the energy potentially stored.

18. The method of storing and dissipating 105 energy from a running motor comprising the expanding of a resilient means, simultaneously trapping a volume of fluid, said volume of fluid serving to maintain the resilient means in its expanded position, and slowly releasing said fluid to utilize the potential energy of the resilient means after the stopping of the motor.

19. A device for temporarily storing 115 energy from a running motor comprising an expandible chamber, resilient means adapted to contract said chamber, a fluid supply under pressure produced by the moving motor for expanding said chamber, automatic 120 means for trapping said fluid under pressure upon a reduction of pressure in said fluid supply, said means being adapted for a bleeding action after the trapping of said fluid whereby the energy utilized in expanding 125 said resilient means is temporarily stored.

20. A priming device for a motor com-

prising a storage chamber for a priming charge of fuel, means to contract said chamber to a relatively small volume upon operation of the motor thereby forcing substantially all of said charge into the motor, means thereafter to maintain said chamber in its contracted state during the operation

of the motor, said means being adapted to gradually expand said chamber upon stopping the motor thereby drawing a charge of 10 fuel into the storage chamber.

In testimony whereof, I have hereunto set my hand.

IRVEN H. WILSEY.
